UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 26, 1926. Serial No. 131,627.

My invention relates to railway traffic controlling apparatus, and particularly to apparatus of the type comprising a plurality of sections of railway track separated by insulated joints and each provided with governing means controlled by current supplied to the rails of the section. One object of the invention is to prevent improper operation of the governing means for a section by stray current from an adjacent section.

I will describe several forms of railway traffic controlling apparatus embodying my invention, and will then point out the novel features thereof in claims.

15 In the accompanying drawing, Fig. 1 is a diagrammatic view illustrating one form of apparatus embodying my invention. Figs. 2 and 3 are views showing modified forms of the apparatus illustrated in Fig. 1 and 20 also embodying my invention.

Similar reference characters refer to similar parts in each of the several views.

Referring first to Fig. 1, the reference characters 1 and 1^a designate the track rails 25 of a stretch of railway track over which traffic normally moves in the direction indicated by the arrow. These rails are divided into a plurality of successive track sections A—B, B—C, etc. by short intermediate portions of track each designated by the reference character D with an exponent corresponding to the location and separated from the adjoining track sections by insulated joints in the track rails. For example, the 30 short intermediate portion D^b, dividing section A—B from section B—C, is isolated from the rest of the track by means of two insulated joints 12 and 14 in rail 1 and by two similar insulated joints 13 and 15 in rail 40 1^a. The two rails of each intermediate portion D are connected together by a jumper 19.

Each track section is provided with a suitable source of alternating track circuit current here shown as a track transformer designated by the reference character T with a distinguishing exponent and having a secondary 6 connected across the rails adjacent the exit end of the section. The primary 7 of each track transformer T is constantly supplied with alternating current from a secondary 9 of an associated line transformer designated by the reference character J with an exponent corresponding

to the location. An impedance 8 is interposed between secondary 9 of each transformer J and primary 7 of the adjacent track transformer T. The primary 10 of each line transformer J is at all times supplied with alternating current from a suitable source such as an alternator M over line wires 3 and 3^a.

Each track section is also provided with a track relay designated in general by the reference character R with a suitable exponent and comprising two windings 4 and 5, one of which, 5, is connected across the rails adjacent the entrance end of the section. The remaining winding 4 of each track relay R is constantly supplied with alternating current from secondary 9 of the adjacent line transformer J.

Each track section is therefore provided with a track circuit including the secondary 6 of a track transformer T, winding 5 of a track relay R, and the rails of the section 75 in series, so that when the section is unoccupied the track relay is energized but that when the section is occupied the track relay becomes de-energized.

The track relays R may be used to control traffic governing means in any suitable manner. As here shown, each track section is provided with a trackway signal designated by the reference character S with an appropriate exponent and each capable of indicating "proceed" or "stop". Each signal S is controlled by the associated track relay R. For example, when relay R^b is energized, current is supplied to the operating mechanism of signal S^b from a secondary 9 of transformer J^b over front contact 11 of relay R^b, and the signal indicates proceed. When relay R^b is de-energized, however, the circuit is interrupted and the signal indicates stop.

As shown in the drawing, section A—B and the section to the right of point C are unoccupied and a train, indicated diagrammatically at V, occupies section B—C. Relays R^c and R^a are therefore energized so 100 that signals S^c and S^a indicate proceed, but since relay R^b is de-energized, signal S^b indicates stop.

Under some conditions it may happen that one or more of the insulated joints 12, 13, 14 or 15 breaks down. In this event, the track

relay for one section may become improperly energized by stray current by an adjacent track section even though the former section is occupied by a train. For example, I will assume that insulated joints 12 and 14 adjacent point B both break down. Current may then flow from the left-hand terminal of secondary 6 of transformer T^B , through rail 1 of section A—B, insulated joint 12, rail 1 of intermediate portion D^B , insulated joint 14, rail 1 of section B—C to the winding 5 of relay R^B , rail 1^a of section B—C, and thence through the ground to rail 1^a of section A—B and back to the right-hand terminal of secondary 6 of transformer T^B . The stray current thus supplied to winding 5 of relay R^B might be of sufficient magnitude to energize the relay. If this should occur signal S^B might indicate proceed, even though section B—C were occupied by a train.

In order to prevent this undesirable occurrence, I connect the mid-point of the secondary 6 of each transformer T with one rail of the adjacent intermediate portion D . Referring particularly to transformer T^B , the mid-point of secondary 6 of this transformer is connected with rail 1^a of the intermediate portion D^B . Due to the jumper 19, the mid-point of secondary 6 is of course electrically connected also with rail 1 of the intermediate portion D^B . With this arrangement, should either of the insulated joints 12 or 13 break down, a portion of the secondary of transformer T^B would be short-circuited and track relay R^A would become de-energized, thereby causing signal S^A to indicate stop. Similarly, should insulated joints 12 and 13 both break down, the entire secondary 6 of transformer T^B would be short-circuited and relay R^A would become de-energized as explained above. Furthermore, should insulated joints 14 and 15 adjacent point B both break down, a direct shunt would be placed upon winding 5 of relay R^B , thereby making it impossible for this relay to become energized by stray current from section A—B. With the apparatus embodying my invention, therefore, it is impossible for a track relay for one section to become energized by stray current from an adjacent section due to a broken down insulated joint.

In the apparatus shown in Fig. 2, a fuse 17 is interposed between rail 1^a of each intermediate portion and the mid-point of secondary 6 of the adjacent track transformer T . Each section is also provided with a detector relay designated by the reference character K with an appropriate exponent. Referring particularly to relay K^B , this relay has one terminal connected directly with the right-hand terminal of track transformer T^B and the remaining terminal of the detector relay is connected with rail 1^a of

the intermediate portion D^B . The parts are so proportioned that under normal conditions the current supplied to the detector relay through the fuse 17 is not sufficient to blow out the fuse. Referring particularly to the apparatus located at point B, should either or both of insulated joints 12 or 13 break down, the increased current through fuse 17 due to the short circuit then placed upon the secondary of transformer T^B would blow out the fuse 17, thereby interrupting the circuit for relay K^B and allowing this relay to open. The front contact 16 of relay K^B controls the supply of current to winding 4 of track relay R^B so that relay R^B can not become energized unless relay K^B is also energized, even though current is supplied to winding 5 of the relay. It follows that if stray current is being supplied to winding 5 of relay R^B from section A—B due to a broken down insulated joint, relay R^B cannot operate improperly, because the broken down insulated joint causes fuse 17 to blow out and open relay K^B , thereby interrupting the circuit for winding 4 of relay R^B . It is therefore impossible to cause signal S^B to give a false proceed indication as the result of a broken down insulated joint between section B—C and section A—B.

Under some conditions means are also provided for supplying each track section with train controlling loop current which flows through the rails of the section in parallel. As shown in Fig. 3 the immediate source of this train controlling current for each section is a transformer designated by the reference character L with an appropriate distinguishing exponent corresponding to the location, and having its primary 22 constantly supplied with alternating current from line wires 3 and 3^a. Each track section is also provided with an impedance 20 connected across the rails adjacent the entrance end of the section and a second impedance 18 connected across the rails adjacent the exit end of the section. Referring particularly to section A—B, the left-hand terminal of secondary 21 of transformer L^B is connected with the mid-point of impedance 20 and the right-hand terminal of this secondary is connected through an impedance 23 with rail 1^a of the intermediate portion D^B . Rail 1 of intermediate portion D^B is connected with the mid-point of impedance 18. Loop current from transformer L^B therefore flows through impedance 23, rail 1^a of intermediate portion D^B , jumper 19, rail 1 of intermediate portion D^B , through the two halves of the impedance 18 in parallel, and the rails of section A—B in parallel, back through the two halves of the impedance 20 to secondary 21 of transformer L^B . The train controlling current supplied to the rails by the transformers L may be used to control train carried govern-

ing means in any suitable manner. In at least one form of apparatus suitable for co-operation with the trackway apparatus illustrated in Fig. 3 the simultaneous supply of track circuit current and train controlling loop current is necessary to give a proceed indication on board the train. Should the supply of either of these currents be interrupted, a stop indication is received on board the train.

In a railway traffic controlling system of the type described should either joint 12 or 13 adjacent point B break down, one half or the other of impedance 18 would be short-circuited. The fluxes in the two halves of the impedance would then be unbalanced and the impedance would constitute a short circuit across the rails of section A—B, thereby shunting the transformer T^B , and interrupting the supply of track circuit current to the rails of the section. Should a train enter the section A—B under these conditions it would receive a stop indication due to the absence of track circuit current. If either of insulated joints 14 or 15 breaks down, stray current from section A—B could not be supplied to relay R^B , because, under this condition the potential applied from section A—B to section B—C would be the same as the ground potential of section A—B and there would therefore be no potential available to supply current to winding 5 of relay R^B . Furthermore, should the jumper 19 become broken, or should the connection between rail 1 of intermediate portion D^B and the mid-point of impedance 18 become broken, or should any other fault occur in the circuit for transformer L^B , the train controlling loop current would be interrupted and a stop indication would be received on board the train.

It follows from the foregoing that in each of the several views the short intermediate portion of track having its rails connected with the mid-point of an impedance (impedance 18 or secondary 6) connected across the rails of the section next in rear checks the condition of the adjacent insulated joints and makes it impossible for stray current flowing from one track section to an adjacent track section due to a broken down insulated joint to create a dangerous condition.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a stretch of railway track divided into two track sections by a

short intermediate portion of track separated from both such sections by insulated joints in the track rails, a jumper for connecting the rails of such intermediate portion together, an impedance connected across the rails of one section, means for connecting an intermediate point of the impedance with a rail of the intermediate portion, means for creating an alternating electromotive force across the rails of such one section, and a relay connected across the rails of the other section.

2. In combination, a stretch of railway track divided into two track sections by a short intermediate portion of track separated from both said sections by insulated joints, a transformer having its secondary connected across the rails of one said section, means for connecting the mid-point of said secondary with both rails of the intermediate portion, means for supplying alternating current to the primary of such transformer, and a track relay having a winding connected across the rails of the other section.

3. In combination, a stretch of railway track divided into two track sections by a short intermediate portion of track separated from both said sections by insulated joints, a transformer having its secondary connected across the rails of one said section, means for connecting the mid-point of said secondary with both rails of the intermediate portion, means for supplying alternating current to the primary of such transformer, a detector relay connected across a portion of said secondary, a track relay having one winding connected across the rails of the other section, and means controlled by said detector relay for supplying alternating current to the remaining winding of the track relay.

4. In combination, a stretch of railway track divided into two track sections by a short intermediate portion of track separated from both said sections by insulated joints, a transformer having its terminals connected with the rails respectively of one said section, means including a fuse for connecting the mid-point of said secondary with both rails of said intermediate portion, means for supplying alternating current to the primary of said transformer, a detector relay having one terminal connected with a rail of the intermediate portion and the other terminal connected with a terminal of the secondary, a track relay having a winding connected across the rails of the other section, and a second winding on the track relay provided with a circuit including a front contact of the detector relay.

In testimony whereof I affix my signature.

HOWARD A. THOMPSON.
